(57) **CLAIM**

The ornamental design for a table as shown and described.

DESCRIPTION

FIG. 1 is a front-right perspective view of a table according to the claimed design.

FIG. 2 is a front-left perspective view of the table.

FIG. 3 is a rear-left perspective view of the table.

FIG. 4 is a rear-right perspective view of the table.

FIG. 5 is a front view of the table.

FIG. 6 is a rear view of the table.

FIG. 7 is a right side view of the table.

FIG. 8 is a left side view of the table.

FIG. 9 is a top view of the table.

FIG. 10 is a bottom view of the table.

FIG. 11 is an enlarged view of area 11 shown in FIG. 7 with the pedals in an unengaged configuration.

FIG. 12 is an enlarged view showing the pedals of FIG. 11 in a first engaged configuration.

FIG. 13 is an enlarged view showing the pedals of FIG. 11 in a second engaged configuration; and,

FIG. 14 is an enlarged view showing the pedals of FIG. 11 in a third engaged configuration.

The dash-dot broken lines in the drawings illustrate portions of the table that form no part of the claimed design. The dash-dot-dot broken lines in FIGS. 7 and 11–14 depict boundaries of the enlarged views that form no part of the claimed design.

1 Claim, 13 Drawing Sheets
